(57) **CLAIM**

The ornamental design for a weight scale assembly with pedestal, as shown and described.

DESCRIPTION

FIG. 1 is a front view of the present weight scale assembly with pedestal design;

FIG. 2 is a rear view of the present weight scale assembly with pedestal design;

FIG. 3 is a left side view of the present weight scale assembly with pedestal design;

FIG. 4 is a right side view of the present weight scale assembly with pedestal design;

FIG. 5 is a top view of the present weight scale assembly with pedestal design;

FIG. 6 is a bottom view of the present weight scale assembly with pedestal design, and;

FIG. 7 is a perspective view of the present weight scale assembly with pedestal design; and,

FIG. 8 is an enlarged view of the display of the present weight scale assembly with pedestal design.

The broken line showing of structural features is included for the purpose of illustrating non-claimed subject matter and forms no part of the claimed design.
